(57) CLAIM

I claim the ornamental design for a watch case with jewels, as shown and described.

DESCRIPTION

FIG. 1 is a front view of a first embodiment of a watch case with jewels showing my new design;

FIG. 2 is a rear view of the watch case with jewels shown in FIG. 1;

FIG. 3 is a bottom perspective view of the watch case with jewels shown in FIG. 1;

FIG. 4 is a top view of the watch case with jewels shown in FIG. 1;

FIG. 5 is a bottom view of the watch case with jewels shown in FIG. 1;

FIG. 6 is a left side view of FIG. 1; and,

FIG. 7 is a right side view of FIG. 1.

The broken line in FIG. 2 is for illustrative purposes only and does not form part of the claimed design.
